BRAIDING MACHINE

Willard W. Bardsley, Providence, R. I., assignor to
 Wardwell Braiding Machine Company, Central
 Falls, R. I., a corporation of Maine

Application January 3, 1933, Serial No. 649,790

15 Claims. (Cl. 96—17)

This invention relates to improvements in braiding machines for producing tubular braids such as used for sleeving, for reinforcing rubber hose or for covering wire and like electrical conductors. More particularly, the invention consists in a strand manipulator and braid-softener, so-called, for controlling the disposition of the braided strands to form a relatively loosely braided fabric.

10 One object of the invention is to provide means for controlling the disposition of the strands as they merge in the fabric being braided.

Another object of the invention is to provide control means which act to maintain the braiding angle of the strands substantially constant to produce a more uniform braid.

Another object of the invention is to provide means for raising or lifting the braiding strands at intervals during their passage into the fabric 20 to prevent them from catching and dragging at the crossing points to impose undue tension thereon.

Another object of the invention is to provide in a machine of the type specified a central mandrel or former around which the strands are braided in relatively tight formation and the tubular braid thereafter pushed off either in the form of sleeving or as a braided covering which is loose on its core.

30 Another object of the invention is to provide a strand-controlling and braid-softening device of simple construction, proof against derangement or getting out of order and which may be easily applied to machines already in use without material change in the construction thereof.

Further objects of the improvement are set forth in the following specification which describes a preferred embodiment of the invention, by way of example, as illustrated by the accompanying drawings. In the drawings:

Fig. 1 is a front elevation of a braiding machine embodying the improved features of the present invention;

Fig. 2 is a vertical sectional view through the central turret of the machine and illustrating the strand-controlling or beater elements in depressed position;

Fig. 3 is a similar sectional view showing the beater device in raised position at the completion 50 of the stroke to lift the strands;

Fig. 4 is an enlarged plan view of the central turret of the braiding machine shown with a portion of its cap or cover broken away to illustrate the mechanism enclosed therein;

55 Fig. 5 is a plan view of the driving means for

the beater, part-sectional on line 5—5 of Fig. 2;

Fig. 6 is a detailed view of one of the cams for operating the beater;

Fig. 7 is a side view of the braid-softener and beater;

Fig. 8 is a perspective view of the beater dome and softener mandrel shown in disassembled relationship;

Fig. 9 is a perspective view of the annular stationery strand support with which the beater parts cooperate; and

Figs. 10, 11, 12 and 13 are plan views showing the relationship of the crossing strands as they lead to the braid and illustrating the manner in which their crossing points are periodically shifted by means of the vibrating beater device.

The invention is herein shown as applied to a machine of the type described and illustrated in United States Letters Patent No. 1,602,442, dated October 12, 1926, wherein two sets of yarn-supplies are arranged in tiers and revolved in opposite directions about the axis of the machine. The strands of yarn from the supplies of the upper tier lead directly to the braiding point and the strands from the lower supplies are caused to pass over and under the supplies of the upper set to perform the braiding operation. It is to be understood, however, that the present improvements may be applied to other forms of braiding or like machines.

Referring first to Fig. 1 of the drawings, the braiding machine as herein shown is mounted upon a frame 2 supported from the floor by legs 3 and comprises oppositely rotating heads 4 and 5 carrying upper and lower supply-carriers 6 and 7. The carriers 6 and 7 carry the supply-packages P and P' from which the yarn, thread or other strand material feeds upwardly to the braiding point of the machine. The upper packages P are arranged circumferentially of the head 4 with their axes inclined toward the vertical axis of the machine and the strands y drawing off from the supplies pass through tension-devices, indicated generally by the reference character 10, and thence lead to the braiding point to be enmeshed in the braid. The lower packages P' are supported on the carriers or brackets 7 spaced about the head 5 with their axes arranged substantially at right-angles to the axes of the upper packages P. The strands y' from the packages P' pass through tension-devices 11 and thence draw upwardly to the fabric being braided. During the revolution of the supplies in opposite directions about the axis of the machine the strands from the lower packages

P' are caused to pass over and under the upper carriers 6 by the operation of means as shown and described in the patent above referred to. The machine is driven from a shaft 12 journaled 5 in a bracket 13 at one side of the frame 2 and carrying a pulley 14 which may be belted to a motor or other suitable source of power. The inner end of the shaft 12 is connected to drive the heads 4 and 5 through the means of gearing 10 in the manner as illustrated in the prior patent before referred to.

In braiding machines of the type herein illustrated the core *w* upon which the covering is braided, or in other cases the tubular fabric itself, is fed through the machine by means of a take-up reel or capstan 15. The capstan 15 is journaled on a stud-shaft 16 fast in a cross-strut 17 extending diagonally across the top of the machine and supported by uprights or standards 18 rising from the frame 2. The capstan 15 is driven from the machine by means of gearing as next described. A pinion-gear 19 on the machine drive-shaft 12 meshes with a larger gear 20 fast on a shaft 21 which is journaled in the bearing bracket 13. Keyed to the end of the shaft 21 is a gear 22 which meshes with a similar gear 23 connected to a sprocket 24. The sprocket 24 is connected by a chain 25 to drive a sprocket 26 fast on a shaft 27 which is journaled in a bearing 28. Keyed to the opposite end of the shaft 27 is a change-gear 29 which meshes with a larger change-gear 30 on a shaft 31. The hub of the gear 30 carries a sprocket 32 which is connected by a chain 33 to drive a sprocket 34 fast on the end of an upper shaft 35. The shaft 35 is journaled in a bearing in the cross-strut 17. At its opposite end the shaft 35 carries a small pinion gear 36 which meshes with a ring-gear 37 on the side of the rim of the capstan 15. 40 It will be understood that through the gear train and chain connections above described the capstan 15 is driven from the drive-shaft 12 at a reduced rate of speed to take up the braided product which is fed therefrom to a wind-up reel, not shown, in accordance with the usual arrangement. The rate of feed of the braided material is governed by the speed of revolution of the braiding carriers, the diameter of the core and the size of yarn being braided to produce a fabric having the required number of picks or crosses per inch. To vary the feed the speed of the capstan may be altered by substituting gears of different ratio for the change-gears 29 and 30.

The operation of the machine is manually controlled by means of a starting handle 38 connected to a shipper-arm 39 for operating a clutch, indicated generally at 40 in Fig. 1. The clutch 40 connects the pulley 14 rotatively with the shaft 12 to drive the heads 4 and 5 which revolve the supply-carriers 6 and 7 in their orbits. Suitable stopping mechanism is usually provided for arresting the operation of the machine when a strand breaks or its supply is exhausted, such a form of mechanism being shown and described 65 in United States Letters Patent No. 1,085,369, dated January 27, 1914.

The strand-manipulator and braid-softener of the present invention is organized with the braiding machine in the manner as next described. 70 Referring to Figs. 2 and 3, 42 designates a central hollow post or axial bearing member which is stationary with the frame of the machine and about which the heads 4 and 5 rotate. The axial bore of the post 42 is lined with a bushing 43 having an annular flange 44 secured to the top of the post

by screws 45. Held fast within the bore of the bushing 43 is a tubular sleeve 46 extending upwardly therefrom to support a tubular mandrel or former 50 which serves as an element of the braid-softener.

The forming mandrel 50 about which the strands are enmeshed or braided takes the form of a nozzle-shaped tube having a lower enlarged base 51 which is exteriorly threaded to screw into the upper interiorly threaded end of the sleeve 46. 85 The upper shank portion 52 of the mandrel 50 has its periphery tapered to adapt the tubular fabric to slide off from its end after the strands are braided therearound. The base of the mandrel 50 has its axial bore flared outwardly at the bottom to form a bell-shaped mouth for facilitating the threading of the core *w* through the tubular shank 52 in preparing the machine for operation. The shank 52 of the mandrel 50 is shouldered at 55 to form an enlarged cylindrical bearing 54 below its tapered portion. A plurality of grooves 53 are formed in the cylindrical portion 54 of the mandrel 50 to provide keyways for a reciprocable dome 82 to be later described. Referring to Figs. 7 and 8, the mandrel 50 as herein shown is adapted to accommodate a core of circular cross-section and of relatively small diameter but in other cases it may be much larger and take different forms. For example, when a rectangular, elliptical or polygonal core is to be covered a mandrel having similarly formed outer and inner contours may be provided.

Surrounding the upper end of the sleeve 46 is a bushing 57 formed with a circumferential flange 58 at its lower end which rests upon the flange 44 of the bushing 43. The bushing 57 is slotted circumferentially at 56 and split longitudinally on one side as shown at 59 in Figs. 2 and 5 to provide a resilient section adapted to be clamped tightly around the sleeve 46 by means to be later described. Rotatably mounted on the bushing 57 and abutting its bottom flange 58 is a gear 60 having an annular rim formed with beveled teeth. The gear 60 constitutes the driving element for actuating the beater mechanism in the manner as later explained. The gear 60 is formed with a radial arm 61 adapted to engage with the side of a stud 63 projecting upwardly from the turret-like top of the head 4 whereby the gear is rotated by and with the head. The stud 63 projects upwardly through an arcuate slot 64 in the top of the turret, see Fig. 4, to adapt it for adjustment circumferentially of the head to time the action of the beater synchronously with the movement of the yarn-carriers. A nut 65 on the stud 63 secures the latter in adjusted position.

Clamped around the bushing 57 above the annular gear 60 is a spider-member 68 formed with a plurality of arms 69 radiating from a central hub 70, see Fig. 4. The hub 70 is split at 71 and provided with ears 72 through which extends a binding screw 73. The screw 73 serves to clamp the spider-member 68 to the bushing 57 and the latter in turn contracts the split section of the bushing around the inner sleeve 46. In this manner the bushing 57 and spider-member 68 are secured fast to the inner sleeve 46 which is stationary with the post 42. The ends of the radial arms 69 of the spider-member 68 are recessed at 74 to provide seats for engagement with an annular shouldered seat 75 on the inside of a cap 76 which is supported thereon above the top of the turret on the head 4. The cap 76 serves as a cover for enclosing the operating elements of the beater and is provided with an upwardly projecting ring 150

or annulus 77 fitted to an interior seat 78 therein. The upper rim of the ring 77 is rounded on its edges to provide a smooth rest or support for the strands of yarn as they draw thereacross in feeding to the braid.

Supported from the spider-member 68 is a second inner ring or annular rest for the strands consisting in a cylinder 79 formed with depending legs 80 as shown in detail in Fig. 9. The legs 80 of the annulus 79 are fastened to an upper vertical flange-portion 81 of the spider-member 68 by means of screws 83, see Fig. 2. The upper rim of the annulus 79 is positioned slightly above the top of the outer ring or annulus 77 on the cap 76 as defined by the inclination of the strands leading thereacross to the braiding point.

The strands drawing across the fixed rings or annuli 77 and 79 in feeding to the braiding point cross and recross each other in pairs as the yarns y' from the lower supplies are deflected over and under the yarns y from the upper set of supplies by the braiding action. As the crossing points of the strands approach the rim of the outer annulus 77, and likewise that of the inner annulus 79, in passing into the braid the crosses tend to catch on the rings to impede their progress into the braid. This will result in a drag which augments the tension on the strands to draw them tighter and cause irregularities in the braided fabric. In such conditions, as the crosses are finally released to slide over the rings the tension on the strands will be suddenly relieved to further disturb the uniformity of the braid. It is one object of the present invention to preserve the uniformity of the braided fabric by preventing the crosses in the strands from catching or being impeded as they pass into the braid and for this purpose a reciprocating beater is provided to periodically lift the strands off from their rests or supports to free the crosses so that their passage into the fabric will be unhindered.

Referring particularly to Figs. 2, 3 and 7, the beater device 84 as embodied in the present machine comprises essentially a vertically reciprocable ring or annulus 85 disposed concentrically with and between the outer fixed annulus 77 and the inner fixed annulus 79. The beater 84 is shown in detail in Fig. 7 of the drawings as comprising a cylindrical portion 85 surrounding the inner fixed ring 79 and provided with three depending arms 86, only one of which is shown in the drawings, by means of which it is reciprocated. Also forming a part of the beater 84 is an inner annulus or cylindrical shell 87 which surrounds the central sleeve 46 and is adapted to slide up and down thereon. Surmounting or capping the inner annulus or shell 87 is the dome 82, previously referred to, which is fitted to a reduced seat on the beater and removably secured thereto by means as later described. The top of the dome 82 is of spherical shape projecting above the top of the ring or annulus 77 and provided at its axis with a circular aperture 88 through which the forming mandrel 50 projects. The rim of the aperture 88 in the dome 82 is formed with teeth or prongs 90 projecting radially into the grooves 53 in the mandrel 50 whereby to key the dome thereto to prevent it from rotating therearound. Preferably, the upper surface of the dome 82 is scored with a series of concentric grooves 91, thus providing that the strands drawing thereacross to the braid are relieved of frictional contact with the full surface of the dome.

The lower cylindrical skirt of the dome 82 is formed with a bayonet-slot 95, as illustrated most

clearly in Fig. 8 of the drawings, and in the lower edge of the lateral portion of the slot 95 is an arcuately shaped depression or notch 96. A stud 97 riveted through the annular shell 87 of the beater 84 projects radially therefrom for engagement with the bayonet-slot 95 in the skirt of the dome 82. It will be noted that the lateral portion of the slot 95 is tapered and by turning the dome in clockwise direction the stud 97 is caused to slide into the narrower portion of the slot to force it into the depression or notch 96. A spanner wrench may be used for turning the dome, being provided with prongs for engaging holes 99 in the sides of the dome. In this way the dome 82 may be attached to the beater after the latter is in place while providing for its convenient removal therefrom when occasion requires. It is further noted that since the dome 82 is keyed to the mandrel 50 by the prongs 90 engaging the grooves 53 in the latter, the mandrel will be turned with the dome in securing the latter in position and consequently the threaded base of the mandrel is not seated before the dome is applied to position.

The arms 86 depending from the beater 85 are bowed outwardly and then extended downwardly to slide in vertical slots 100 in the hub of the spider-member 68, see Figs. 2 and 3. Riveted through the lower end of each arm 86 is a shouldered stud 101 which serves as a journal for a bowl 102. The rollers 102 journaled on the arms 86 are engaged with undulating cam-grooves 104 in three disks 105, see Figs. 5 and 6, carried by the spider-member 68. The cam-disks 105 have hubs secured rotatively to inner sleeves 106 by means of keys 107 as shown in Figs. 2 and 3. The sleeves 106 are journaled on pins 108 projecting from radial bosses 109 on the sides of the hub of the spider-member 68 and secured in the bosses by cross-pins 110. Washers 111 are held 115 against the outer ends of the hubs of the cam-disks 105 by means of cotter pins 112 engaged in holes in the ends of the journal pins 108. The sleeves 106 project axially from the sides of the cam-disks 105 to abut the ends of the bosses 109 and take the form of beveled pinions having teeth on their peripheries engaging the teeth of the driving gear 60. Through these connections the cam-disks 105 are rotated from the turning movement of the gear 60 with the heads 4 and 5 and the cam-grooves 104 are thereby caused to reciprocate the beater with a relatively rapid oscillating motion as the heads 4 and 5 revolve in opposite directions about the axis of the machine.

The method of operation of the complete machine is as next explained. To prepare the braider for operation a mandrel 50 of suitable form and size is selected and applied to the top of the machine by screwing its base 51 into the end of the sleeve 46 until its shouldered portion brings up 130 against the top thereof. The mandrel 50 is then turned back in the reverse direction approximately two full turns and the dome 82 placed over its end and slid downwardly thereon with its prongs 90 engaging the grooves 53. As the dome 82 is slid downwardly the stud 97 on the beater 84 is entered into the vertical portion of the bayonet-slot 95 and by manually turning the dome the stud is caused to slide into the lateral portion of the slot to engage with the notch 96 to lock the 145 parts in connection.

When a core such as a wire, represented in the drawings at w , is to be covered with braid, or in other cases when the braided covering is to be applied to a rubber tube or hose pipe, the core is 150

led upwardly from its supply reel, not herein shown and passed through the axial opening of the machine and the bore of the mandrel 50 as shown in Figs. 2 and 3. The leading end of the 5 wire *w* or other core is then passed around the rim of the take-up wheel or capstan 15 to cause it to be fed through the machine when the broiding operation is started.

The supply-packages *P* and *P'* of yarn, thread, 10 cord or other strand material are applied to the upper and lower carriers 6 and 7 and the strands *y* and *y'* drawn off therefrom and passed through the tension-devices 10 and 11 to lead to the broiding point above the top of the dome 82. The ends 15 of the strands may be fastened to the mandrel 50 or otherwise secured to hold them until the broiding operation commences.

To start the broiding operation the handle 38 is manually shifted to clutch the pulley 14 to the 20 drive-shaft 12. Through the connections before described the shaft 12 rotates the heads 4 and 5 in opposite directions to revolve the supply-packages *P* and *P'* about the axis of the machine. To effect the broiding action the strands *y'* from 25 the lower supplies are deflected from a normal course to pass them alternately over and under the upper strands *y* in the prescribed order to form the broid in accordance with the desired pattern. Simultaneously with the turning movement of the 30 heads 4 and 5 the capstan 15 is rotated to feed the core *w* through the machine and deliver the broided product to a wind-up reel, not herein illustrated. The strands *y* and *y'* draw across the upper rim of the fixed rings 77 and 79 as they lead 35 to the broiding point which is normally located above the shouldered portion 55 of the forming mandrel 50. The strands are enmeshed by the broiding action to form a tubular broid *b* enclosing the mandrel 50 which, as before noted, tapers toward its upper end so that the fabric may be 40 readily slid off therefrom. As the mandrel is greater in circumference than the wire or other core to which the fabric *b* is applied its use results in a relatively loose fabric on the core. That is to say, while the strands may be broided tightly 45 about the mandrel as is required to secure a smooth, uniform fabric, when the tubular broid is slipped off from the mandrel it will be relatively loose on the core. Likewise, if no core is used, when the tightly broided tubular fabric is slipped 50 off from the mandrel it becomes relatively loose and soft without tendency of the strands to draw together to reduce its size. The feeding of the core or the broided tube under the action of the capstan tends to draw the fabric *b* off from the 55 mandrel but actually the tubular broid is pushed upwardly to feed it off the end of the mandrel by the reciprocating action of the dome 82, carried by the beater 84, which is intermittently raised against the strands as they merge into the fabric.

The beater and broid-softener cooperate with the broiding mechanism of the machine in the manner as next explained. During the rotation of the heads 4 and 5 the gear 60 is driven from the head 4 to effect rotation of the cam-disks 105 at a relatively rapid rate. The cam-disks 105 act through the arms 86 to vertically reciprocate the beater 84 whereby to rapidly oscillate its ring 85 and the dome 82. The effect of the oscillation of these parts is to periodically lift the strands from 70 their supports on the fixed rings 77 and 79, the purpose being to free the strands at their crossing points so as to prevent the crosses from catching and impeding the progress of the yarns 75 into the broid. This action is illustrated more or

less diagrammatically in Figs. 10 to 13 of the drawings as viewed in connection with Figs. 2 and 3. In Fig. 10, which is a plan view of the operating elements of the beater device, the strands of yarn *y* and *y'* are shown in position corresponding to their relationship to the parts as illustrated in Fig. 2 of the drawings. That is to say, at this point in the operation of the machine the strands *y* and *y'* rest across the edges of the fixed rings 77 and 79 and those of each pair are crossed at a point outside of the periphery of the outer fixed ring 77. With the strands thus disposed their crosses will tend to catch or drag on the edge of the ring 77 to impede their progress into the fabric. To prevent such a contingency the operation of the beater device is so timed that before the crosses in the yarns reach the location shown in Fig. 10 the beater ring 85 starts to rise to the position shown in Fig. 3 of the drawings. That is to say, as the crosses reach the rim of the outer fixed ring 77 the beater-ring 85 rises and lifts the several pairs of crossing yarns away from the top of the fixed rings 77 and 79; the dome 82 being also simultaneously raised to lift the strands at the point where they merge in the 100 broid. Under this action the crosses will advance inwardly to the edge of the beater-ring 85 as shown in Fig. 11. The beater is now depressed or slid downwardly whereby the strands will again rest on the two fixed rings 77 and 79, the position 105 of the crosses at this juncture being illustrated in Fig. 12 of the diagrammatic views.

It has been explained that the movement of the beater is very rapid and, consequently, before the crossing points of the yarns advance to the 110 edge of the inner fixed ring 79 the beater-ring 85 is once again moved upwardly to lift the strands away from the ring 79. This action occurs with the strands related as shown in Fig. 12. After the crossing points of the strands have passed inwardly beyond the fixed ring 79 the beater is depressed once more and finally the crosses rest on the grooved crown of the dome 82 as indicated in Fig. 13 of the diagrammatic views. At this point in the broiding operation the rapid oscillation of the beater prevents the crosses in the strands from being retarded in their advance to the fabric being broided. The purpose of the 120 grooves 91 on the dome is, as before noted, to relieve the friction on the strands by providing a 125 plurality of contact points rather than an extended surface.

During the continuation of the broiding operation the beater device functions as above explained to intermittently raise the strands off 130 from their fixed rests to insure the unhindered progress of their crosses into the broid. Meanwhile, the oscillating action of the dome 82 causes the broid *b* to be continuously pushed or urged upwardly on the tapered mandrel 50 so that it 135 will feed off from the end thereof to enclose the core passing through the axial bore of the mandrel or, in other cases, to assume the form of loosely broided sleeving.

In order that the beater may function properly in synchronism with the broiding action it must be timed accurately with the other going elements of the machine. The timing of the beater is effected by adjusting the angular relationship of the gear 60 with respect to the driving 145 head 4, this adjustment being accomplished by sliding the stud 63 in its slot 64. The closeness or density of the broid is regulated by the size of the yarn and the diameter of the lower portion of the tapered shank 52 of the mandrel 50 where the 150

braiding action takes place. The degree of constriction of the braid on the core is governed by the rate of feed of the fabric off the mandrel in relation to the rate of feed of the core; it being noted that to render the fabric loose on the core it must be fed from the mandrel at a rate faster than that of the advance of the core. To regulate this characteristic of the braided product the ratio between the speed of rotation of the capstan and the speed of the revolving supplies is adjusted by means of the change-gears 29 and 30.

It will be observed from the foregoing that the present invention provides a highly efficient, automatic machine for fabricating tubular coverings for wire, hose pipes and other cores, or for producing soft-braided sleeving. The mandrel provides a fixed former around which the strands may be braided under relatively heavy tension whereby to permit high speed operation of the machine to secure a rapid rate of production and a uniform product. The operation of the machine may be controlled to produce a tubular fabric having the strands braided uniformly about a central core with any desired degree of looseness or tightness thereon. A loose braid of this nature is of advantage for covering wire or other conductors which are first sheathed with soft insulating material such as unvulcanized rubber and also for reinforcing hose pipe before its rubber walls are vulcanized.

The present machine has various other uses such, for example, as braiding soft coverings on telephone cords or the like to render them more pliable and for producing tubular braid which may be used as sleeving adapted to numerous purposes.

While the invention is herein illustrated and described in a preferred form of construction and as applied to a particular type of machine, it is to be understood that various modifications may be made in the form and arrangement of the parts of the device and in its application to use without departing from the spirit or scope of the invention. Therefore, without limiting myself in this respect, I claim:

1. In a braiding machine, the combination of braiding mechanism, a central support, a forming mandrel projecting axially from said support, an annulus surrounding the mandrel in spaced relation thereto and reciprocable on the support, a dome carried by said annulus in axial relation thereto and provided with an opening through which the mandrel projects, and means for reciprocating the annulus to oscillate the dome longitudinally of the mandrel.

2. In a braiding machine, the combination of braiding mechanism, a support arranged axially of the braiding mechanism, a forming mandrel projecting axially from said support, an annular member surrounding the mandrel in spaced relation thereto and reciprocable on said support, a member carried by said annular member in axial relation thereto and provided with a portion surrounding the axial mandrel, and means for reciprocating said annular member longitudinally of its axis.

3. In a braiding machine, the combination of braiding mechanism, a support arranged axially of the braiding mechanism, an annulus carried by said support and disposed to provide a rest for the strands leading to the braiding point, a second fixed annular rest arranged concentrically of the first annulus, a third reciprocable annulus arranged between the outer and inner annular rests, an inner reciprocable rest arranged axially of said

annuli, and means for reciprocating the third annulus and the inner rest.

4. In a braiding machine, the combination of braiding mechanism, a central post arranged axially of said mechanism, an annular beater reciprocable axially on said post, a member fast on the post, a cam journaled on said member to rotate on an axis extending radially thereof, a follower on the beater engaging the cam, a gear on the cam, and a gear rotatable on the post and meshing with the gear on the cam to rotate the latter.

5. In a braiding machine, the combination of braiding mechanism, a post arranged axially of the machine, a beater reciprocable longitudinally of the post to periodically engage the strands leading to the braiding point, a follower on said beater, a cam journaled to rotate on an axis extending radially of the post and engaging the follower on the beater, a gear on said cam, and a gear driven with the braiding mechanism and meshing with the gear on the cam to rotate the latter.

6. In a braiding machine, the combination of means for interlacing strands to form a braid, an axially arranged mandrel around which the strands are braided, a central strand-rest enclosing the mandrel and reciprocable longitudinally thereof, fixed annular rests arranged concentrically of the mandrel to adapt the strands to draw thereacross in feeding to the braid, a vibratory annulus arranged concentric with and between the fixed annuli, and means to oscillate the vibratory annulus and the central strand rest to periodically lift the strands away from the fixed annuli.

7. In a braiding machine, the combination of means for interlacing strands to form a braid, an axially arranged mandrel around which the strands are braided, fixed annular rests arranged concentrically of the mandrel to adapt the strands to draw thereacross in feeding to the braid, a vibratory annulus arranged concentric with and between the fixed annuli, means for oscillating the vibratory annulus to periodically lift the strands from the fixed annuli, and an element movable with the vibratory annulus and surrounding the mandrel to adapt it to periodically engage the strands adjacent the braiding point to force the braided fabric toward the end of the mandrel.

8. In a braiding machine, the combination of two sets of revolving strand supplies, means for interlacing the strands from the supplies to form a tubular braid, a turret arranged axially of the strand supplies, an outer fixed ring supported from the turret to adapt the strands to draw thereacross in feeding to the braid, an inner fixed ring supported from the turret in concentric relation with the outer ring, a reciprocatory ring arranged between and concentric with the fixed rings, means operated synchronously with the braiding action to reciprocate the vibratory ring to periodically raise the strands away from the fixed rings, and a member carried by the vibratory ring with its upper portion surrounding the mandrel to adapt it to be reciprocated therewith to feed the braided fabric off the end of the mandrel.

9. In a braiding machine, the combination of braiding mechanism, a tubular support arranged axially of the braiding mechanism, a forming mandrel projecting axially from said support, an annular beater reciprocable axially with respect to the mandrel, means for reciprocating

the beater, a dome mounted on the beater with the mandrel projecting through an opening in its top, said dome formed with a bayonet-slot, and a stud projecting from the beater for engagement with the bayonet-slot in the dome to secure the parts in connected relationship.

10. In a braiding machine, the combination of braiding mechanism, a tubular support arranged axially thereof, a tubular mandrel secured in the end of the tubular support, an annular beater reciprocable longitudinally of the tubular support, a dome-shaped member mounted on the beater with the mandrel projecting through an opening in its top, said dome formed with a bayonet-slot in its skirt with a notch in the lateral portion thereof, a stud projecting from the beater to adapt it to be entered into the bayonet-slot in the dome to engage it with the notch therein, and means for reciprocating the beater to oscillate the dome longitudinally of the mandrel.

11. In a braiding machine, the combination of braiding mechanism, a turret extending axially thereof, a tubular support extending axially of the turret, a ring supported from the turret in position to provide a rest for the strands feeding to the braiding point, a member secured to the inner tubular support, an annulus carried on said member in concentric relation with the outer fixed annulus, a beater surrounding the central tubular support and reciprocable longitudinally thereof, said beater formed with an annulus arranged concentric with the fixed annuli, and means for reciprocating the beater to cause its annular portion to raise the strands off from the fixed annuli to prevent their crosses from dragging thereon to impede their progress into the braid.

12. In a machine of the type specified, the

40

combination of a hollow mandrel, means for feeding a core through the mandrel at a predetermined rate, means for applying strands around the mandrel to form a tubular covering for the core, and means for forcing the covering off from the end of the mandrel at a faster rate than the feed of the core whereby to apply it to the core without constriction of the strands thereon.

80

13. In a machine of the type specified, the combination of a hollow mandrel, means for feeding a core through the mandrel at a predetermined rate, means for applying a plurality of strands to the outside of the mandrel to form a covering for the core, and intermittently operated means for pushing the covering off from the end of the mandrel at a faster rate than the feed of the core to apply the covering loosely around the core.

85

14. In a machine of the type specified, the combination of a tubular mandrel, means for feeding a core through the mandrel at a predetermined rate, means for interlacing strands to form a tubular fabric around the mandrel, and means for pushing the fabric off from the end of the mandrel at a faster rate than the feed of the core whereby to prevent the fabric from constricting the core.

90

15. In a machine of the type specified, the combination of a tapered forming mandrel having a longitudinal bore, means for feeding a core through the mandrel at a predetermined rate, means for interlacing strands to form a tubular fabric around the mandrel, and means for pushing the core off from the end of the mandrel onto the core at a faster rate than the feed of the latter to prevent constriction of the fabric thereon.
